UNITED STATES PATENT OFFICE.

CHARLES S. HAMLIN, OF LOS ANGELES, ASSIGNOR OF ONE-HALF TO
ARTHUR C. HARPER, OF UNIVERSITY, CALIFORNIA.

SHEET-METAL PIPE.

SPECIFICATION forming part of Letters Patent No. 507,709, dated October 31, 1893.

Application filed June 1, 1893. Serial No. 476,260. (No model.)

To all whom it may concern:

Be it known that I, CHARLES S. HAMLIN, a citizen of the United States, residing at Los Angeles, in the county of Los Angeles and State of California, have invented new and useful Improvements in Sheet-Metal Pipes, of which the following is a specification.

The object of my invention is to produce a cheap, strong and durable pipe, suitable for conveying water, &c.

My invention is especially adapted for use in preparing pipe from thin sheet metal formed into convolute or partially convolute rolls and spirally wound with wire or strap iron.

My invention broadly stated comprises a pipe consisting of a plate of sheet metal bent upon itself to form two leaves, and having its inner leaf of greater length than its outer leaf and projecting equally beyond each end of the outer leaf, and having its outer leaf of greater width than such inner leaf, the two leaves being rolled into tubular shape and the projecting ends of the inner leaf being turned outward over the ends of the outer leaf to cover the joint between the two leaves, and suitable means for retaining the pipe in shape.

My invention also comprises a pipe consisting of a plate of sheet metal bent upon itself to form two leaves, and having its inner leaf of suitable width to form the sized pipe desired, and having its outer leaf of greater width than its inner leaf, the two leaves being rolled into tubular shape; an S shaped lap strip having one of its folds arranged embracing the bent edge of the two leaves and having its other fold arranged embracing the single edge of the inner leaf; a suitable wrapping arranged to retain the pipe in shape, and the whole covered with a coating of preservative material.

My invention further comprises a pipe consisting of a plate of sheet metal bent upon itself to form two leaves, and having its inner leaf of greater length than its outer leaf and projecting equally beyond each end of the outer leaf, and having its outer leaf of greater width than its inner leaf, the two leaves being rolled into tubular shape; an S

shaped lap strip having one of its folds arranged embracing the bent edge of the two leaves, and having its other fold arranged embracing the single edge of the inner leaf, the projecting ends of the inner leaf being turned outward over the ends of the outer leaf; a suitable wrapping of wire arranged to retain the pipe in shape, and the whole covered with a coating of preservative material.

My invention further comprises various combinations and arrangement of parts hereinafter fully set forth.

The accompanying drawings illustrate my invention.

Figure 1 is a plan view of a sheet of metal cut into shape ready to be folded upon itself to form a length of my improved pipe. Fig. 2 is a view of the same with the inner leaf folded upon the outer leaf, and ready to be passed through the rolls and formed into tubular shape. Fig. 3 is an end view of the sheet formed into tubular shape ready to be wrapped. Fig. 4 is a fragmental side elevation of the same in a different position from that shown in Fig. 3. Fig. 5 is a fragmental perspective view of one end of a pipe constructed according to my invention, illustrating my improved means for securing the end of the wire wrapping. Fig. 6 is a fragmental side elevation of a completed pipe embodying my invention. Fig. 7 is a longitudinal fragmental sectional view of my improved lap joint; line $x-x$ Fig. 3 indicates the line of section. Fig. 8 is a cross section of the same on line $y-y$ Fig. 7. Fig. 9 is a fragmental cross section of a modified form of joint.

In the drawings, A represents the sheet of metal which is cut into the shape shown in Fig. 1, and is then folded as shown in Fig. 2 to form the inner leaf a and the outer leaf a' . The outer leaf a' is of greater width than the inner leaf a to form a lap joint, and to assist in retaining the pipe in shape. The inner leaf is longer than the outer leaf as illustrated in Figs. 1, 2 and 5, to allow the projecting end to be turned back over the end of the outer leaf a' , to form an end cap a'' which prevents the entrance of any water from the end of the pipe into the joint between the leaves of

sheet metal. This construction is clearly illustrated in Fig. 7, where the cap is shown in section. This cap also forms a smooth end for the pipe in addition to making a water tight joint at the end, and also assists in binding the two leaves together and holding the pipe in shape when the joints are driven together when the pipe is laid. In order to gage the diameter of the pipe, and also to provide means for preventing the inner edge of the inner leaf from springing outward into the pipe, I provide one edge of such inner leaf with a suitable edge receiving seat adapted and arranged to receive and seat the other edge of such leaf. As shown in the drawings, this seat consists of an **S** shaped lap strip B which is formed of sheet metal and has one fold b arranged upon and embracing the bent edge a''' of the two leaves, and has its other fold b' arranged upon and embracing the single edge of the inner leaf a. This edge receiving seat may be formed integral with the single edge of the inner leaf, if desired, as shown in Fig. 9, and I do not limit my claims 25 to the use of the independent **S** shaped lap strip.

In wrapping pipe with wire, difficulty has been experienced in providing a suitable fastening for securing the ends of the wire upon 30 the pipe, and various means have been devised to produce a suitable fastening therefor.

I provide an improved fastening for wire wound metal pipe consisting of two or more thicknesses of sheet metal, which consists essentially of a wire C, having one end provided with a rivet receiving loop c and inserted beneath the outer leaf of the pipe (as shown in Fig. 4) when the pipe is formed, thence passing spirally around the pipe to 35 the other end thereof, and provided at such other end of the pipe with an end receiving loop C' formed in the wire, thence passing one or more times around the pipe beyond such loop and having its end C'' passed 40 through such loop and secured by bending the wire backward upon itself. This is illustrated in Fig. 5. After the pipe is formed, a rivet c', (shown in dotted lines in Fig. 6) is inserted through the wall of the pipe, passing 45 through the loop c, and is riveted, thereby securing the other end of the wire between the two leaves of the pipe. By this means I provide a secure fastening for the wire and one which can be made quickly and cheaply.

50 In practice the sheets are prepared for making the pipe by cutting them into the form shown in Fig. 1, then bending the sheet upon itself to bring the two leaves together as shown in Fig. 2, then starting the reversely bent edge a''' of the two leaves into the former rolls and forming the leaves into tubular shape as illustrated in Fig. 3; before the reversely bent edge a''' enters the roll upon its second round, the **S** shaped lap strip B is 55 placed upon such edge with its inner fold embracing the edge in the manner shown in

Fig. 3. Then, as the rolls revolve, the single edge of the inner leaf a is brought into position by the action of the rolls and is inserted into the outer fold of the **S** shaped strip as 70 shown in Fig. 3. Then the joint thus formed is passed through the rolls which tightens the lap strip firmly upon the two edges and forms a tight joint. After the lap strip has passed through the rolls and before the free end of the outer leaf is carried in between the rolls, the end of the wire wrapping C which is provided with the loop c is inserted between the outer leaf and the body of the pipe, with the loop 75 in the position shown in Fig. 4. Then the rolls are revolved to carry the pipe around and the wire is wrapped spirally around the pipe as shown in Figs. 5 and 6 until the other end of the pipe is reached, sufficient tension being placed upon the wire to cause it to bind 80 upon the pipe firmly; when the other end of the pipe is reached, a loop c' is formed in the wire, as illustrated in Fig. 5 and the wire is carried beyond the loop one or more times around the pipe and the end c'' is inserted 85 through the loop c', drawn tight and bent back upon itself, thus firmly securing the wire wrapping in place upon the pipe in an expeditious and effective manner.

The inner leaf a is of just sufficient width 95 to form a pipe of the diameter desired after the two ends are lapped past each other and rest in the lap strip as shown in Fig. 3, and when pressure is applied upon the exterior of the pipe, as in wrapping, the two ends 100 resting in the loops of the lap strip, prevents the pipe from being reduced in diameter by such pressure. The lap strip also holds the inner edge of the pipe from springing out into the pipe, which sometimes occurs in ordinary 105 wire wrapped convolute sheet metal pipe.

The sheet metal plates are lightly coated with asphaltum before being formed into pipe, and melted asphaltum is applied to the joint before it is covered by the outer leaf, 110 and the completed pipe is also dipped in melted asphaltum which fills the seams of the joint and absolutely prevents leakage.

The end cap a'' prevents the entrance of 115 water between the leaves from the end of the pipe, and the over-lapping end of the outer leaf strengthens and protects the joint so that my improved pipe will stand a heavy pressure without liability of leakage, although made of thin light iron.

120 Now, having described my invention, what I claim as new, and desire to secure by Letters Patent, is—

1. The pipe set forth, consisting of a plate of sheet metal bent upon itself to form two 125 leaves, and having its inner leaf of greater length than its outer leaf and projecting equally beyond each end of the outer leaf, and having its outer leaf of greater width than its inner leaf, the two leaves being rolled 130 into tubular shape and the projecting ends of the inner leaf being turned outward over the

ends of the outer leaf to cover the joint between the two leaves and suitable means for retaining the pipe in shape.

2. The pipe set forth, consisting of a plate of sheet metal bent upon itself to form two leaves, and having its outer leaf of greater width than its inner leaf, and having one of the edges of the inner leaf provided with a suitable edge receiving seat adapted and arranged to receive and seat the other edge of such leaf, the two leaves being formed into tubular shape, one edge of the inner leaf being seated in the seat provided upon the other edge of such leaf, a wrapping of wire wound around such pipe, and the whole covered with a coating of preservative material.

3. The pipe set forth, consisting of a plate of sheet metal bent upon itself to form two leaves, and having its inner leaf of greater length than its outer leaf, and having its outer leaf of greater width than its inner leaf, one of the edges of the inner leaf being provided with a suitable edge receiving seat arranged to receive and seat the other edge of such inner leaf, the two leaves being rolled into tubular shape and the projecting ends of the inner leaf being turned outward over the ends of the outer leaf, and a suitable fastening arranged to retain the pipe in shape.

4. The pipe set forth, consisting of a plate of sheet metal bent upon itself to form two leaves, and having its inner leaf of suitable width to form the sized pipe desired, and having its outer leaf of greater width than its inner leaf, the two leaves being rolled into tubular shape; an S shaped lap strip having one of its folds arranged embracing the bent edge of the two leaves, and having its other fold arranged embracing the single edge of the in-

ner leaf; a suitable wrapping arranged to retain the pipe in shape, and the whole covered with a coating of preservative material.

5. The pipe set forth, consisting of a plate of sheet metal bent upon itself to form two leaves, and having its inner leaf of greater length than its outer leaf and projecting equally beyond the ends of the outer leaf, and having its outer leaf of greater width than its inner leaf, the two leaves being rolled into tubular shape; an S shaped lap strip having one of its folds arranged embracing the reversely bent edge of the two leaves and having its other fold arranged embracing the single edge of the inner leaf, the projecting ends of the inner leaf being turned outward over the ends of the outer leaf; a suitable wrapping of wire arranged to retain the pipe in shape, and the whole covered with a coating of preservative material.

6. In a sheet metal pipe consisting of two or more thicknesses of sheet metal, the wire wrapping, having one end provided with the rivet receiving loop and inserted beneath the outer leaf of the pipe when the pipe is formed, thence passing spirally around the pipe to the other end thereof, and provided at such other end of the pipe with an end receiving loop formed in the wire, thence passing one or more times around the pipe beyond such loop and having its end passed through such loop and secured by bending the wire backward upon itself, and the rivet inserted through the wall of the pipe and passing through the rivet receiving loop in the other end of the wire.
